Inventor:

Franklin R. White,
Parker Cook
Atty.

UNITED STATES PATENT OFFICE

FRANKLIN R. WHITE, OF WATERBURY, CONNECTICUT, ASSIGNOR TO THE PATENT
BUTTON COMPANY, OF WATERBURY, CONNECTICUT, A CORPORATION OF CONNECTI-
CUT

BUTTON

Application filed March 29, 1930. Serial No. 440,026.

My invention relates to new and useful improvements in buttons, and has for an object to provide a button that will be extremely strong in service and, at the same time, relatively cheap to manufacture.

One of the objects of the present invention is to produce a one-piece button that may preferably be made out of hard metal, such as stainless steel but, on the other hand, may 10 be made of softer metals, such as aluminum, if so desired.

Still another object of the invention is to produce a one-piece button wherein the hub and head, or face, may be made from bar 15 stock or from stampings, there being a chamber formed in the hub to receive a tack or preferably a staple, and the hub being also so formed or arranged that a cross bar is formed across the chamber, so that the prongs 20 of the staple may be forced around this cross bar or even a tack fastener might be utilized instead of a staple.

Still another object of the invention is to form a one-piece button, the walls of the hub 25 then being forced inwardly to thereby cause the metal to extend from opposite points of the hub toward each other and thus substantially form a cross bar about which the prongs or fasteners may be deformed when the but- 30 ton is attached.

Still another object of the invention is to provide a button formed from bar stock or stampings having a head in which there is formed an integral hub, the side walls of the hub being operated on by adjacent dies to thereby form integral fastening portions across the hub about which the prong or 35 prongs of the fastener may be attached.

With these and other objects in view, the 40 invention consists in certain new and novel arrangements and combination of parts, as will be hereinafter more fully described and pointed out in the claims.

Referring now to the drawings showing a 45 preferred embodiment of the invention and several modifications thereof,

Fig. 1 is a plan view from the under-side of the button;

Fig. 1^a is a sectional view of the button 50 shown in Fig. 1;

Fig. 2 is a similar view to Fig. 1 showing the shape of the hub after the dies have forced the hub to its final shape;

Fig. 2^a is a sectional view thereof;

Fig. 2^b is a sectional view taken at right angles to Fig. 2^a;

Fig. 3 is a plan view from the under surface of the button of a slightly modified form;

Fig. 3^a is a sectional view of the button 60 shown in Fig. 3;

Fig. 4 is a plan view from the under surface of the button of a slightly modified form, a part of the hub being shown in section;

Fig. 4^a is a sectional view of the button 65 shown in Fig. 4;

Fig. 4^b is an edge view taken at right angles to the section shown in Fig. 4^a; and

Fig. 5 shows how a cap may be attached to the head of the button, if so desired, and the 70 shape the staple will take when the button is fastened to the garment.

Referring now more particularly to the drawings, and Figs. 1 to 2^b specifically, there is shown my improved button, comprising 75 the head 1, the integral hub 2, and the chamber 3 within the hub.

If the button is to be made of soft metal, such as aluminum, it may be made from bar stock or wire, which is fed into an automatic 80 heading machine (not shown) cut to length and then moved into the path of cutting dies and swedged, and then subjected to a second set of dies (not shown), to provide the chamber 3 similar, as far as the specification has proceeded, to the button shown in the patent to Forrest G. Purinton, No. 1,496,017, granted June 3, 1924.

Should the button be made of harder metal, such as steel, it may be formed from stampings or possibly a number of actions of heading dies to preliminarily form the button, as shown in Figs. 1 and 1^a.

After this blank is so formed, the same is then subjected to side pressure operation (the dies not being shown) to elongate or flatten the sides of the hub, as at 4, and slightly flare the same, as seen in Fig. 2^b. At the same time, the metal is driven inwardly to 95 form the little inwardly projecting teats 5. 100

and 6 which are spaced a slight distance from the outer edge of the hub. These little teats, as may be seen in Fig. 2^a, by meeting at their point substantially form a cross bar in the hub.

As may be seen in Fig. 5, all that is necessary, therefore, to do to attach this button is to drive a staple 7 down into the chamber or the hub of the button, and the prongs impinging against the bottom wall 8 will direct the prongs upwardly to thus grip about the cross bar formed by the inwardly projecting oppositely disposed teats, to thereby tightly fasten the button to the garment 9.

It will be understood that these buttons are attached in a button attaching machine of the well-known type, wherein the heads are fed from one hopper and the staples from the opposite hopper, and the staple then driven up through the garment and into the hub or fastening receiving member of the button.

Referring now to the slightly modified form, as shown in Figs. 3 and 3^a, there is shown the button comprising a similar head 10 with the integral hub 11 and this preliminarily formed button is then subjected to a header (not shown) to force the upper circular edge of the hub to the outline or configuration shown at 11^a, that is, the two inwardly projecting teats 12 extend across the hub and meet each other at their point, and the hub, then, has the appearance of a figure 8, as may be clearly seen in Fig. 3. In other words, the final shape of the hub in this modified form is very similar to the arrangement shown in the preferred form, but the manner of forming the teats that result substantially in the cross bar is done by a header operation rather than by plungers being driven into the sides of the hub. It will be noticed that these teats 12 extend, or are positioned, slightly nearer the upper edge of the hub than they are in the preferred form, where the teats are formed by tools operated at the opposite sides.

Of course, the hub will have the chamber 13 formed therein, and the manner of driving the staple through the garment will be the same.

Referring for the moment to the form shown in Figs. 4, 4^a and 4^b, the button head 14 is very similar to the button head shown in the preferred and modified form just referred to, one difference in this instance being that the hub 15 remains circular in cross section with the exception, however, at the place where the two teats 16 are struck. In other words, instead of flattening out the side walls of the hub, they are left circular in outline, so that the only metal displaced is the metal that forms the oppositely extending teats.

Another difference from the preferred form is that the two teats 16 are rectangular in cross section rather than circular. In other words, the two tools (not shown) that

are driven into the side of the hub will be blunted or rectangular in shape rather than be pointed.

It will be understood, of course, that if desired, where the cross bar is substantially rectangular in section, the hub might have its sides flattened rather than circular, as just described or, on the other hand, the button shown in the preferred form might have the cross bar formed of the rectangularly-shaped teats rather than the two inwardly projecting conical teats.

It might be here mentioned that all of the views show the buttons greatly exaggerated in size, but simply for the sake of illustration.

In Fig. 5, a cap 17 is shown over the button head and this cap may be of an ornamental nature and have any desired insignia thereon.

From the foregoing, it will be seen that I have formed a button or button head out of one piece of metal which may either be formed of bar stock or stamping, and having a fastener receiving chamber formed in the integral hub of the button. In this chamber there is formed a cross bar about which the prongs of the staple will be secured. Furthermore, this forming of the cross bar is either accomplished by striking metal inwardly from the sides of the hub or by subjecting the hub to a header operation to thus force some of the metal inwardly to form the cross bar, the results being practically the same in both instances.

I am aware that it is old to make buttons of somewhat similar types of several pieces, wherein a separate cross bar is put in, or wherein a cross bar is cut from stamped metal, but I am not aware of a button head formed of but one piece and certain portions of the metal of the hub forced inwardly of the hub to thereby provide a cross bar about which the fastener may be secured.

Many slight changes might be made without in any way departing from the spirit and scope of the invention.

Having thus described my invention, what I claim as new and desire to secure by Letters Patent is:

1. A closed top metal button having an integral hub, a portion of the metal of the hub being struck inwardly from the opposite sides of the hub to thereby substantially form an integral cross bar.

2. A closed top button having an integral metal hub, a portion of the metal of the side walls being struck inwardly towards each other to thereby substantially form an integral cross bar.

3. A solid head button having an integral hollow metal hub, inwardly projecting indentations formed in the hub, and the said indentations being directly opposite each other to thereby substantially form an integral cross bar in the hub.

4. A solid button having an integral hollow metal hub, oppositely located indentations formed on the side walls of the hub and spaced slightly from the solid head, and the metal from the indentations forming a substantially integral cross bar in the hub, and the side walls of the hub at the places of indentations being slightly flattened.

5. A solid head button comprising an integral hollow hub and a head, a part of the metal of the opposite side walls being forced inwardly to substantially form a cross bar, and the inwardly forced metal being rectangular in cross section and the bottom wall of the hub acting as an anvil and adapted to turn the prong of a fastener about said bar.

6. A solid head button having an integral hollow hub formed of metal, oppositely located indentations formed in the hub, and the resultant displaced metal forming lateral projections in the hub, the lateral projections substantially forming a cross bar in the hub and adapted to cooperate with a fastener member, the bottom wall of the hub adapted to act as a deflecting wall for a fastener member.

7. A button having an integral hollow hub formed of metal, oppositely located indentations formed in the hub, the hub being slightly flattened at the places of indentations and slightly flared at the resultant opposite ends, the said indentations forming lateral projections that substantially meet in the hub to thus substantially form a cross bar in the hub and the bottom wall of the hub adapted to act as a deflecting means for the prongs of a fastener.

8. A one-piece button comprising a head and an integral hollow hub, opposite portions of the side walls of the hub being struck inwardly, and the displaced metal forming laterally projecting teats to thus substantially form a cross bar within the hub and about which may be secured a fastening member and the inner dome of the hub adapted to act as a deflecting wall for a fastener member.

In testimony whereof I affix my signature.

FRANKLIN R. WHITE.
